UNITED STATES PATENT OFFICE.

LEWIS F. RAMSEY, OF KANSAS CITY, MISSOURI.

TITLE. BEST AVAILABLE COPY

1,413,684.

Specification of Letters Patent. Patented Apr. 25, 1922.

Application filed October 29, 1920. Serial No. 420,458.

To all whom it may concern:

Be it known that I, LEWIS F. RAMSEY, a citizen of the United States, residing at Kansas City, in the county of Jackson and 5 State of Missouri, have invented certain new and useful Improvements in Tiles; and I do declare the following to be a full, clear, and exact description of the invention, such as will enable other skilled in the art to which 10 it appertains to make and use the same, reference being had to the accompanying drawings, and to the letters and figures of reference marked thereon, which form a part of this specification.

15 This invention relates to building tile and it is applicable for use in building silos and the like although it is also adapted for use in building partition walls, facing walls, or, indeed, in any structures where building tile 20 are adapted to be employed.

The invention contemplates a hollow, interlocking, single-webbed tile, the adjacent tile being adapted to interlock one with the other to form a continuous wall, the tile being 25 preferably arranged in courses and, if desired, the inner spaces formed by the interlocking webs may be insulated and braced as will appear by reference to the following description in connection with the accompanying 30 drawings, in which—

Fig. 1 is a fragmentary, perspective view of a silo constructed in accordance with my invention.

Fig. 2 is a detail view of one of the tie 35 rods for bonding adjacent tile.

Fig. 3 is an end view of a straight walled tile structure.

Fig. 4 is an inside perspective view of one of the tile constructed in accordance 40 with my invention.

Fig. 5 is an outside perspective view of the same.

Fig. 6 is a fragmentary, perspective view 45 of a modified form of tile, showing weather facings.

Fig. 7 is an end view of a wall constructed of tile as shown in Fig. 3 with insulating material within the hollow spaces formed by the tile, and

50 Fig. 8 is an end view showing insulating strips secured to the tile and rods for bonding the tile together.

Each tile is preferably formed of a single piece having a main web portion 1 and a 55 transverse extension or web portion 2. The web portion 1 preferably extends longitudi-

nally of the wall or structure while the portion 2 is shown as arranged at right angles thereto to provide an interlocking tongue 3 adapted to engage a tongue-receiving groove 4 in an adjacent tile, the interlocking portion in which the groove 4 is formed being on the inner face of the longitudinal web 1. The groove 4 is preferably undercut to receive the undercut tongue 3 so that when the adjacent tile are brought together, they will be interlocked, as clearly apparent by reference to Fig. 3.

The longitudinal web 1 is also formed with an inter-locking tongue 5, which is 70 slightly inclined with respect to the main portion 1 and it is adapted to engage in a tongue-receiving groove or notch 6 in the outer face of the web portion 2 and preferably at the angle or point of connection 75 of the portion 2 with 1. The structure thus formed provides a hollow, interlocking, single-web tile, the connecting tiles forming air spaces or hollow portions 7, which may be utilized as dead air spaces, filled with 80 cement or similar filling 8 if desired (see Fig. 6).

The tile shown in Fig. 1 are substantially the same as those shown in Figs. 3, 4 and 5 except that the longitudinal faces of the 85 inner tile are slightly shorter than the outer faces of the outer tile, this being desirable in order to form the circular structure.

The tile may be bonded together by inverted, U-shaped tie rods 9, one of which is 90 indicated in detail in Fig. 2.

In Fig. 6 I have shown a slightly modified form of tile consisting of the longitudinal web portions 10 and the transverse web portions 11, substantially the same as shown 95 in Figs. 3, 4 and 5 with the exception that the outer faces of the tile have inclined, offset portions 12 to form facing or weather tile.

In Fig. 7 the construction is substantially that shown in Fig. 3 except that the insulating strips 13 are diagonally arranged in the air spaces 7 and the tile are preferably tied by diagonal bonds 9, there being a filling material 14 between the strips 13 and the faces of the tile.

100 In Fig. 8 the longitudinal faces 1' are substantially the same as shown in Fig. 5. The transverse web portions 2', however, are provided with vertical ribs 15 to be engaged by the recesses 16 on the insulating strips 17. 110 These strips may be of any number, dependent upon the width of the web portions

2' so I do not wish to be limited to the exact number shown. The webs 2' may be bonded together, however, by bonds 9, as clearly shown and, if desired, a filling may 5 be placed between any of the spaces formed by the strips 17.

It will be apparent that the tile may be arranged in courses or staggered to form lap joints, the latter arrangement being accomplished by arranging the first course of tile 10 of different heights; for example, by cutting each alternate tile in half, then the rest of the tile may be arranged in the usual way so that lap joints will be formed, as shown 15 in Fig. 1. This is the preferred arrangement since the structure will be tied better than if the tile are laid in straight courses.

In assembling the tile, each added tile is split vertically in interlocking engagement 20 with the preceding tile so that the tongues 3 will engage in grooves 4. The two adj-

acent tile at the end may be connected by a web portion 18 consisting of a fragment cut from one of the portions 1. This is shown in Fig. 3.

25

What I claim and desire to secure by Letters-Patent is:

A tile wall comprising a plurality of tiles, each of which is provided with a long leg and a short leg, the long leg having a tongue-engaging groove on its inner face and in the transverse center thereof and the short leg of each tile having a groove-engaging tongue to engage the groove in the center of the long leg of a complementary tile, the ends of the 30 long leg being curved to engage a groove in the outer face of the short leg of a complementary tile, the free ends of the long legs of all the tiles extending in the same direction.

35

In testimony whereof I affix my signature.

LEWIS F. RAMSEY.
